No. 617,062.

Patented Jan. 3, 1899.

J. D. TALIAFERRO.
INSULATING ARM.

(Application filed June 18, 1898.)

(No Model.)

UNITED STATES PATENT OFFICE.

JOHN D. TALIAFERRO, OF LOUDON, TENNESSEE.

INSULATING-ARM.

SPECIFICATION forming part of Letters Patent No. 617,062, dated January 3, 1899.

Application filed June 18, 1898. Serial No. 683,837. (No model.)

To all whom it may concern:

Be it known that I, JOHN D. TALIAFERRO, a citizen of the United States, residing at Loudon, in the county of Loudon and State of Tennessee, have invented certain new and useful Improvements in Insulating - Arms; and I do hereby declare the following to be a full, clear, and exact description of the invention, such as will enable others skilled in the art to which it appertains to make and use the same.

This invention relates to insulating-supports for electric conductors; and the object is to provide an improved construction of arm adapted for use on telegraph-poles or in other locations, which arm will not only be equipped with wire-holding insulators at suitable distances apart, but will also provide for insulation in the event of the wires becoming displaced from such insulation.

To this end the invention consists in certain novel features of construction and combinations of parts recited in the appended claims and preferred forms of embodiment of which are shown in the accompanying drawings, forming part of this specification.

Of said drawings, Figure 1 represents a cross-arm constructed in accordance with my invention and applied to a telegraph-pole. Fig. 2 represents in longitudinal section, on an enlarged scale, that portion of the cross-arm on one side of the pole, together with a portion of the pole. Figs. 3 and 4 are cross-sections taken on lines III III and IV IV of Fig. 2. Fig. 5 is a view similar to Fig. 1, illustrating a modification.

In the accompanying drawings the reference-letter *a* designates a round metal rod which forms the core of the arm and which 40 may occupy a hole made transversely through the telegraph-pole *z*, as shown in Fig. 2, or it may have a flattened central portion *a'*, as shown in Fig. 5, bolted against one side of the pole, or it may be suited in some other 45 way for attachment to an appropriate support.

Where the arm is for application to a telegraph-pole, it is made to extend on both sides of the same, and the rod is screw-threaded at 50 each end, as shown at *a*², to receive nuts *b*, for a purpose hereinafter explained.

Insulators are strung along the rod, and

each insulator comprises a glass annulus *c*, circumferentially grooved, as shown at *c'*, and beveled on each side of the grooves, and 55 a bushing *d*, of wood or other suitable material, exteriorly screw-threaded to engage screw-threads in the bore of the glass annulus. These insulators are spaced apart and kept separate by means of glass sleeves *e* 60 embracing the rod, and similar sleeves *e'* surround the rod between the telegraph-pole and the insulators nearest thereto. The nuts *b* applied to the ends of the rod bear against the outermost insulators and clamp all the 65 insulators and sleeves together. The wires are engaged with the grooves of the insulators and tie-wires are employed in the ordinary way; but, as is well known, the tie-wires sometimes work loose and allow the electric 70 conducting-wires to slip from their places. With my construction the arm is completely insulated and displacement of the wires cannot result disastrously, for the spacing-sleeves *e* and *e'* are of insulating material 75 and will afford a bearing-surface for the wires in the event of their disengagement from the grooves of the insulators.

The compactness and practicability of the entire structure here shown will be noted and 80 the fact that it is susceptible of ready adaptation to different needs.

While I have mentioned glass as the material of which the spacing-sleeves and grooved insulating-annuli are composed, it is to be understood that other insulating material may 85 be used. Moreover, the invention may be embodied in structures differing more or less from those shown in the accompanying drawings without involving a departure from the 90 spirit and scope of the invention.

The grooved insulators may be made without wooden bushings, and the arm may be braced by a bracket-piece underneath if found preferable to making the center rod large 95 enough to dispense with any such additional support.

In Fig. 5 washers *x*, of vulcanized rubber, are shown interposed between the sleeves and the insulators, and similar washers may be 100 introduced between the post and sleeves, and one may well be interposed between the clamping-nut and the end insulator, especially where the latter has no wooden bush-

ing. The short sleeves x' (shown in Fig. 5) between the innermost insulators and the flattened portion of the rod may be advantageously made of vulcanized rubber the same 5 as the washers x .

Having thus fully described my invention, what I claim as new, and desire to secure by Letters Patent of the United States, is—

1. An insulating-arm comprising a horizontal supporting rod or core of metal, annular insulators strung upon the same and having encircling wire-holding grooves, spacing-sleeves of insulating material surrounding the rod between said annular insulators, and 15 means for holding latter and the sleeves together on the rod.

2. An insulating-arm comprising a metal supporting rod or core, annular insulators strung upon said rod and having wooden 20 bushings, and spacing-sleeves of insulating material covering the rod between said annular insulators.

3. An insulating cross-arm for telegraph-

poles, comprising a metal rod for engagement with the pole, sleeves of insulating material 25 strung along said rod, annular insulators applied to the latter between the sleeves, and means for clamping the sleeves and insulators together on each side of the pole.

4. The combination of a pole having a transverse opening through it, a metal rod passing through said opening and having screw-threads at its ends, insulators strung upon said rod, spacing-sleeves of insulating material covering the rod between the insulators 35 and between the innermost ones of the latter and the pole, and nuts applied to the ends of the rod and clamping the sleeves and insulators together.

In testimony whereof I affix my signature 40 in presence of two witnesses.

JOHN D. TALIAFERRO.
